UNITED STATES PATENT OFFICE.

JOHN GATELY, OF CHICAGO, ILLINOIS.

DESIGN FOR A RUG.

SPECIFICATION forming part of Design No. 32,117, dated January 16, 1900.

Application filed December 20, 1899. Serial No. 741,026. Term of patent 7 years.

To all whom it may concern:

Be it known that I, JOHN GATELY, a citizen of the United States, residing at Chicago, State of Illinois, have invented and produced a certain new and original Design for a Rug, of which the following is a full, clear, and exact description, reference being had to the accompanying drawing, forming a part of this specification.

My invention relates to the surface ornamentation of a rug; and it consists of the design therefor shown in the accompanying drawing.

Its essential and distinguishing features are a central spherical figure illustrating the globe floating in space and on the right-hand

side thereof a beehive and on the left-hand side thereof a tent. Surrounding the whole and near the parallel edges is a small vine-like figure, and within the same and surrounding the tent and beehive are small clusters of floral figures.

I claim as my invention—

The design for a rug substantially as shown and described.

In testimony whereof I have hereunto affixed my signature this 6th day of December, A. D. 1899.

JOHN GATELY.
